(57) **CLAIM**

The ornamental design for a double wall dome lid, as shown and described.

DESCRIPTION

FIG. 1 is a top perspective exploded view, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof shown in a combined state; and,

FIG. 10 is another perspective view thereof, shown in a condition of use.

The broken lines in the drawings illustrate the portions of the double wall dome lid, which form no part of the claimed design.
